UNITED STATES PATENT OFFICE.

PIERRE DIEBOLD, OF NANCY, FRANCE.

IRONING STEAM PRESS.

Application filed June 18, 1927, Serial No 199,852, and in France October 14, 1926.

This invention relates to steam presses for ironing clothes and other articles, and it refers more particularly to the method of suspension and the construction of the movable upper plate of the press.

The upper plate, in a steam press, is generally connected to its supporting arm by an articulated joint giving it the necessary freedom of movement for compensating 10 the inequalities of thickness of the material of the clothing or garment, and the consequent inequalities of pressure at different points of the surface of the plate.

One method of suspending the plate consists in the use of springs combined with V-shaped ribs or knives provided either on the supporting arm or on the plate, and determining between the said two members, lines of support extending at right angles to the 20 longitudinal axis of the plate, about which lines the said plate can swing within the limit permitted by the springs. This means is however insufficient for ensuring uniform distribution of pressure throughout the 25 whole surface of the plate, as though it allows of a swinging of the plate in longitudinal direction, it does not possess sufficient flexibility to allow also of a swinging in the transverse direction. An excessive unequal pressure on the plate is liable therefore 30 to produce its fracture.

One object of this invention is to remedy the said drawback and it consists, whilst retaining the well known principle of spring 35 suspension, in doing away with the supporting V shaped ribs and in replacing them by a central pivot such as a ball, a pin with spherical head or its equivalent, enabling the plate to move in any direction and therefore 40 bringing about equalization of pressure throughout the whole extent of the surface of the plate.

The risk of fracture of the plate thus being decreased, it becomes possible to make 45 it lighter and, more particularly to reduce its height. Another object of the invention is to facilitate the manufacture of this hollow body of small thickness and for this purpose the plate is made, according to the 50 invention, in two pieces, a main body and a cover plate, this method of manufacturing making it possible to provide in the main body a system of ribs or baffles which cause the steam or other heating fluid to follow 55 a rational path across the plate.

Another object of the invention relates to

a connection by special flexible tubes between the upper plate of the press and the frame of the latter, as such a flexible connection is necessary because of the mobility of the said plate. According to the invention said flexible tubes, instead of being made of helically wound metal bands which will allow leakage of steam, are made of a single piece of metal, and the tubes are so shaped as to 60 have corrugations in the direction of the longitudinal section of the tubes, which corrugations impart to the tubes the desired flexibility and avoid any leakage of steam.

In the accompanying drawing:

Fig. 1 is a side elevation, with sections, of an ironing press provided with the improvements referred to;

Figs. 2 and 3 are a vertical section and a plan of the suspension of the upper plate;

Fig. 4 is a partial front elevation of the press, partly in section;

Fig. 5 shows the body of the plate in plan.

In said figures, *a* is the supporting arm terminating in the plate-holder *b* to which 80 is attached the upper plate *c*. According to the invention, the fixing of the plate *c* to the plate holder *b* comprises several angle irons *d* and a certain number of suspension springs *e* with central guide rods *f* which 85 rest on a flange *g* of the plate holder. The portion of the plate *c* which is situated below the holder *b* is recessed as indicated at *h*, and in the center of the recess is arranged a boss *i* with a small spherical seat in which 90 is mounted a ball *k*, generally of steel, interposed between the said boss *i* and the plate holder *b*.

By reason of this ball as well as the recess *h* which extends under the whole surface of the plate holder, the press plate can swing 95 in any direction, longitudinally as well as transversely, and adapt itself to any inequalities of thickness of the article of clothing to be pressed. In order to prevent the plate 100 from rotating about its pivot, there is provided a finger *m* secured to the plate holder and engaging with a groove *n* provided in the plate *c*.

On account of the mobility of the plate *c* 105 it is not possible to use the ordinary system of rigid pipes with articulated steam joint for the admission of steam to the said plate and for the return of water of condensation, and it is necessary to connect the frame of the press to the upper plate by flexible tubes as shown at *w* and *x* in Figure 1,

where w is the steam admission tube and x the return tube. Tubes of this kind have been already used for steam presses, but as they are made of a helically wound metal band, leakage of steam through the turns takes place after a short period of service. To avoid this drawback, according to the invention use is made of flexible metal tubes made in a single piece and provided in the direction of their longitudinal section with corrugations as shown in Figure 1, which give to these tubes a much greater flexibility than that of tubes formed of spiral bands, and the tubes thus made are not liable to allow leakage of steam at any point of their length. The use of these tubes improves the conditions of working with the press.

With reference more particularly to Figures 4 and 5, the plate which as will be seen is of a reduced thickness, is made in two pieces, that is to say the body p forming the heating chamber, is made independently of the cover plate already designated by the letter c . This construction makes it possible to cast the ribs or baffles r, s, t which force the heating fluid, steam or other, to pass right through the chamber between the inlet u and the outlet v .

What I claim is:

1. In an ironing steam press, a movable arm pivotally connected with the frame of the press, a flanged plate holder at the outer end of the arm for supporting the upper plate of the press, and a ball joint connection between the plate holder and the upper plate of the press consisting of a ball seat at the

center of the lower face of the flanged plate holder, a boss at the center of the top face of the press plate, a ball seat in the boss, a steel ball bearing on the seats in the boss and the plate holder, and means for movably attaching the plate of the press to the flanged plate holder. 40

2. In an ironing steam press, a movable arm connected with the frame of the press, a flanged plate holder for supporting the upper plate of the press, an upper plate for the press, a ball joint between the plate and its plate holder, and means for movably attaching the upper plate of the press to the flanged plate holder, consisting of brackets extending upwards from the upper face of the plate close to the flanged plate holder, guide rods on the brackets and suspension springs around the guide rods bearing at 55 one end against the brackets and at the opposite end against the flanges of the flanged plate holder.

3. In an ironing steam press having a ball joint connection between the upper plate of the press and the plate holder, means for preventing the plate from rotating about said ball joint connection, consisting of a recessed central part in the upper face of the plate, a groove opening into the recessed 60 central part, a plate holder extending into the recessed central part of the plate, and a finger attached to the lower face of the plate holder, said finger engaging the groove which opens into the central recessed part of 65 the plate to prevent the rotation of the plate. 70
